UNITED STATES PATENT OFFICE

98,313

DESIGN FOR A FOOD CHOPPER

Roger W. Griswold, Erie, Pa., assignor to The Griswold Manufacturing Company, Erie Pa., a corporation of Pennsylvania

Application November 1, 1935, Serial No. 59,321

Term of patent 14 years

To all whom it may concern:

Be it known that I, Roger W. Griswold, a citizen of the United States, residing at Erie, in the county of Erie and State of Pennsylvania, have invented a new, original, and ornamental Design for a Food Chopper, of which the following is a specification, reference being had to the accompanying drawing wherein:—

Fig. 1 is a side elevation of the food chopper showing my new design.

Fig. 2 is a front elevation.

Fig. 3 is a rear elevation.

I claim:—

The ornamental design for a food chopper as shown.

ROGER W. GRISWOLD.
